UNITED STATES PATENT OFFICE.

KUWAKICHI FUJITA, OF HAZLETON, PENNSYLVANIA.

BURGLAR-ALARM.

1,368,791.

Specification of Letters Patent. Patented Feb. 15, 1921.

Application filed October 10, 1919. Serial No. 329,683.

To all whom it may concern:

Be it known that I, KUWAKICHI FUJITA, a subject of the Emperor of Japan, residing at Hazleton, in the county of Luzerne and State of Pennsylvania, have invented new and useful Improvements in Burglar-Alarms, of which the following is a specification.

This invention relates to burglar alarms and more particularly to the class of devices disclosed in applications filed by me. One application was filed April 24, 1918, and bearing Serial No. 230,539 and the other application was filed November 19, 1918, bearing Serial No. 261,191.

The chief object of this invention is to improve and simplify devices of this character and to employ electro-magnetic means in connection with the cartridge firing mechanism.

With the above and other objects in view the invention resides in the combination and arrangement of parts hereinafter more fully described and illustrated in the accompanying drawing, in which:—

Figure 1 is a perspective view of the device being incased as shown.

Fig. 2 is a plan view, the casing having been removed.

Fig. 3 is a plan view showing the positions the various parts assume when the cartridges are being discharged.

Fig. 4 is a sectional view taken on the line 4—4 of Fig. 2.

Fig. 5 is a sectional view taken on the line 5—5 of Fig. 3.

The device consists of a base 10 having bearings 11 in which is mounted a shaft 12. Arranged for swinging movement on the shaft 12 are housings 13 each of which having arranged therein a metal barrel 14. A metal plate 15 is arranged adjacent one end of each barrel and is provided with a central opening to admit a cartridge 16, the flange 17 of the shell seating itself against the face of the plate 15. A plate 18 is arranged for sliding movement adjacent the plate 15 and acts in the nature of a breech device. Each plate 18 is provided with a small hole 19 for a purpose to appear. Arranged relatively to the housings 13 and secured to the base 10 is a block 20 having arranged on the upper face thereof, a lever 21, the lever being pivotally mounted as at 22 and is provided with firing pins 23. This lever, it will be seen may be moved

to a position for firing of the cartridges or the same may be moved to a non-firing or safety position. Powerful springs 24 are employed which have a tendency to swing the housings 13 and their cartridges over the lever 21 to cause the pins 23 to function for the discharge of the cartridges as will be understood.

In order that the housings may be held in the position shown in Fig. 4 of the drawings the device is provided with a holding device 25 which is connected at one end as at 26. Each housing is provided with an arm 27 which engages the device 25 as at 28. The free end of the device 25 is provided with a loop 29. A releasing member 30 is swingingly mounted as at 31 and in the position of the device 25 shown in Fig. 2, said member overlies the bight of the loop 29. The free end of the member 30 is engaged by the nose 32 of a dog 33.

The discharge of the cartridges is caused by the devices and in a manner presently described. An electro-magnet 34 is arranged on the base 10 and is in such position that when the device 25 is set, the magnet 34 will be disposed within the loop 29. The magnet 34 is arranged on a block 35 which is provided with plates 36 having bearings 37 which receive pins on a rocking beam 37. The beam 37 has one end 38 thereof disposed adjacent the core 39 of the magnet and the opposite end 40 of said beam is provided with a brass piece 41 and as shown in Fig. 4 of the drawing, the piece 41 engages the dog 33. A small spring 42 serves to hold the piece 41 in engagement with the dog 33. The coil of the electro-magnet 34 is in circuit with a battery 43 and a circuit closer 44. The circuit closer 44 may be arranged so as to be actuated by a door or a window. Energization of the core 39 attracts the end 38 of the beam 37 which causes the piece 41 to clear the end of the dog 33. The dog being made of resilient material is then attracted by the opposite end of the core 39 freeing the member 30 and the holding device 25 and thus permitting the housings 13 having the cartridge barrels 14 therein, to swing over the lever 21 for the firing of the cartridges.

These devices may be arranged in dwellings or out-houses, such as garages and hen-roosts. The circuit closer of the device may be disposed in operative relation with a door or other closure through which entrance

may be obtained so that upon the opening of such closure the device will immediately be brought into action to frighten or scare away an intruder.

5. What is claimed as new is:—

1. A burglar alarm, including in combination, a plurality of movable barrels each adapted to receive a cartridge; cartridge firing means including a pivoted lever having firing pins thereon; means for holding the barrels in inactive positions and electro-magnetic means operable to permit the cartridge firing means to function for the discharge of the cartridges.
- 10 2. A burglar alarm, including in combination, a plurality of housings swingingly mounted each having arranged therein a barrel, a slideable breech device operatively arranged in correlation with each housing adjacent one end of its barrel; cartridge firing means including a pivoted lever having firing pins thereon; means for holding the barrels in inactive positions and electro-magnetic means operable to permit the firing pins to function for the discharge of the cartridges.
- 15 3. A burglar alarm, including in combination, a plurality of movable barrels each adapted to receive a cartridge to be fired,

cartridge firing means, means including a releasing member for holding the barrels in inactive positions, and electro-magnetic means comprising a coil having a core, a rocking beam, a non-magnetic piece secured to one end of said beam, a resilient magnetizable dog engageable with said releasing member, the non-magnetic piece normally interposed between the core and the end of said dog.

4. A burglar alarm, including in combination, a plurality of movable barrels each adapted to receive a cartridge to be fired, cartridge firing means, means including a releasing member for holding the barrels in inactive positions, and electro-magnetic means comprising a coil having a core, a magnetizable rocking beam, a non-magnetic piece adapted to be interposed between the core and one end of said dog to prevent attraction of said dog by the core, one end of said rocking beam disposed to be attracted by the core when the same is energized to permit the dog to be attracted by said core when energized, for the purpose specified.

In testimony whereof I have affixed my signature.

KUWAKICHI FUJITA.
